UNITED STATES PATENT OFFICE.

CHESTER M. CUNNINGHAM, OF PEORA, WEST VIRGINIA.

BOX-FASTENER.

SPECIFICATION forming part of Letters Patent No. 605,401, dated June 7, 1898.

Application filed July 26, 1897. Serial No. 645,922. (No model.)

To all whom it may concern:

Be it known that I, CHESTER M. CUNNINGHAM, of Peora, in the county of Harrison and State of West Virginia, have invented certain new and useful Improvements in Crate-Fastenings; and I do hereby declare the following to be a full, clear, and exact description of the invention, such as will enable others skilled in the art to which it appertains to make and use the same.

This invention relates to new and useful improvements in fastenings for crates, and especially in providing, in connection with the cross-strips of the cover, a bolt having a hook at its free end which is designed to engage with the free end of a spring-actuated bolt mounted in a casing fastened by suitable means to the cross-strip of the crate, a suitable pin being provided, which is attached to the said spring-actuated bolt for the purpose of disengaging the bolts from their locked relation.

To these ends and to such others as the invention may pertain the same consists, further, in the novel construction, combination, and adaptation of parts, as will be hereinafter more fully described, and then specifically defined in the appended claim.

In the accompanying drawings, Figure 1 is a perspective view of a portion of a crate, showing the improved device applied in connection therewith. Fig. 2 is a sectional view through the crate and the locking mechanism. Fig. 3 is a detail perspective view of the opposite parts of the fastening shown applied to portions of the crate.

Referring to the drawings, wherein similar numerals of reference are employed to indicate corresponding parts in the several views, the numeral 1 designates a lid or cover for a crate or analogous device, and secured to the opposite ends thereof is a depending cross-strip 2, in which is mounted a bolt 3, which extends below the lower edge of the said cross-strip and at its lower end is reduced, as at 4, and formed with a catch-lip 5. In the accompanying drawings but one end of the crate is shown; but it will be understood that the device is to be applied to both ends or at opposite sides, as the case may be. The said bolt 3 is formed of metal and has a flat head 6 to keep it in position, and to assist in preventing

the said bolt turning, it is substantially rectangular in cross-section.

In the upper part of the body of the crate 55 or other containing-receptacle cross-strips 7 are secured and are formed with vertical openings 8, extending therethrough, of the same form, but slightly larger than the bolt 3. The under side of each of the cross-strips 7 is mortised, as at 9, and therein is mounted a tubular casing 10, preferably of rectangular shape and having located therein a sliding spring-actuated latch 11, with a depending operating-pin 12 attached thereto and movable in a slot 13 in the bottom of the said tubular casing. The nose of the latch 11 extends over the lower termination of the opening 8, and the casing is so situated relatively to the said opening that by operating the pin 12 the said latch will be turned inwardly into its casing and clear the said opening to permit the bolt 3 to pass therethrough, and after said bolt has passed through the opening 8 the latch will be permitted to assume its normal position 75 and catch the lip 5 and hold the engaging parts in locked position and until the said latch 11 is again turned backwardly into its socket to free the nose thereof from the said lip 5. The casing 10 is secured in position 80 by a bolt 14, attached thereto, and extends through an opening which exposes the upper end of the said bolt at the upper edge of the said cross-strip 7. A nut 15 is then applied to the said upper end of the bolt 14, and by this 85 means the said casing is securely held in position in the strip. The rear end of the casing is also reduced and formed with a securing-tongue 16, through which a screw or other fastening is passed.

It will of course be understood that in applying the two devices—that is, the bolt 3 in the opening 8—the operation of the latch 11 will be automatic, as the bolt is so constructed as to be shoved backward into its socket by 95 the end of the bolt 3; but when it is desired to release the parts it is necessary to apply a force to the latch 11 through the pin 12. By locating the latch against the under edge of the cross-strip 7 it is protected and cannot 100 be readily engaged by adjacent objects to accidentally release the parts.

It is obviously apparent that many minor changes in the details of construction and ar-

angement of the several parts might be made and substituted for those shown and described without in the least departing from the nature or spirit of the invention.

5 Having thus described the invention, what is claimed as new is—

In a fastener for crates, the combination with the cover of the bolt 3, mounted in an aperture in a cross-strip thereof, the free end 10 of said bolt being reduced and a notch formed therein, of the cross-strip of the crate, the casing secured in a recess in the under side of said cross-strip of the crate, the spring-actuated bolt in said casing, the free end of which 15 bolt is disposed in the path of the hooked end

of bolt 3, and designed to engage with said hooked end, of the pin 12 secured to the head of the bolt extending through a slot in the casing, and the rotary screw 14 fastened at its lower end to the casing, and the nut 15 20 carried on the upper end thereof and countersunk in the cross-strip of the crate, as shown and described.

In testimony whereof I have signed this specification in the presence of two subscr- 25 ing witnesses.

CHESTER M. CUNNINGHAM.
